CERAMIC TRIM TILE

Joseph Stephen Wheeler, Jr., San Diego, Calif.
(814 S. Gilbuck, Anaheim, Calif. 92802)

Filed Feb. 17, 1967, Ser. No. 5,847

Term of patent 14 years

(Cl. D18—2)

FIG. 1 is a perspective view showing the top inner edge and one end edge of my new tile;

FIG. 2 is a perspective view showing the bottom inner edge and the other end edge of my new tile;

FIG. 3 is a top view of the tile that I provide;

FIG. 4 is a bottom view of my new design; and

FIG. 5 is a view of one side of my new tile design.

I claim:

The ornamental design for a ceramic trim tile, as shown and described.
